W. A. LORENZ

CLOSURE FOR CONTAINERS

Filed March 12, 1923

Inventor:
William A. Lorenz

UNITED STATES PATENT OFFICE.

WILLIAM A. LORENZ, OF HARTFORD, CONNECTICUT.

CLOSURE FOR CONTAINERS.

Application filed March 12, 1923. Serial No. 624,462.

To all whom it may concern:

Be it known that I, WILLIAM A. LORENZ, a citizen of United States, residing at Hartford, in the county of Hartford and State 5 of Connecticut, have invented new and useful Improvements in Closures for Containers, of which the following is a specification.

This invention relates to improved means 10 for closing the tops of jars, tumblers or other containers. This closure is adapted for sealing receptacles containing cold products, without the use of a vacuum; or for sealing receptacles by the well known vacuum process. 15

Figure 1 of the drawings represents a plan view of a rectangular piece of sheet metal, with four corners, 8, 8, 8, 8, cut off. Fig. 2 is a sectional view on the line 2—2 20 of Fig. 1, in combination with a gasket and a container. Fig. 3 is an outside view of a cap, drawn from the sheet of Fig. 1, showing shallow and deep rim portions. Fig. 4 is a sectional view on the line 4—4 of Fig. 25 1 after the cap has been completed. Fig. 5 is a sectional view on the line 5—5 of Fig. 1; when the cap has been completed and when the container has been provided with a cap and gasket, and when in position to be sealed. Fig. 6 is a view showing the parts 30 of Fig. 5, when the container has been sealed. In Figs. 5 and 6 the containers are shown in fragmentary form, and they are not shown in a sealing machine.

35 The hermetic sealing of containers of the class usually employed presents difficulties that are quite serious. These comprise the proper seating of the cap and gasket on the jar rim, and holding them in place while 40 pumping air out of the container; this difficulty is increased when substances are to be hermetically sealed that contain much air, like peanut butter; the air causes the substance to ooze out beyond the gasket and 45 causes the cap to assume a crooked position on the tumbler when sealed as in the usual practice.

The object of the present invention is to 50 provide a closure that will hold the gasket upon the tumbler rim with just enough pressure to prevent the contents from oozing out during the air exhausting operation. Another object is to provide mechanical means to hold the closure on the container, 55 when hermetically sealed, in addition to the atmospheric pressure exerted on the closure.

These two objects are accomplished by providing several spring catches. These are formed in the cap rim and are sprung inwardly so as to engage a shoulder on the jar or container. These catches are preferably made of different lengths. The shorter catches hold the gasket on the rim of the container during the sealing operation by engaging the shoulder of the jar, and the longer catches engage the said shoulder when the gasket has been compressed and the cap has been forced down during the sealing operation. Another object of this invention is to make the irregularly rimmed closure or cap with inturned edges so as not to cut the hands when handling the container or removing the cap. This is done by turning the lower edges of the cap rim inwardly. Another object of this invention is to provide a closure that can be closed by pressure exerted on the cap, without the necessity of a vacuum seal. This is accomplished by engaging the spring catches under the shoulder of the container after the cap has been 80 pressed down on the gasket. Another object comprises the packing of hot products by the well known method of processing. This is accomplished by heating the container, pouring the hot product into the container, putting the cap in place; putting a weight on the top of the cap until the contents cool, and thereby engaging the catches with the jar shoulder.

The container 10 may be of any desired 90 form; it is provided with a rounded rim 11, and a shoulder 12. In the drawings a tumbler is shown, whose rim 11 may be fire finished, if preferred.

The closure or cap 14 of Fig. 3 is formed 95 from the approximately rectangular blank 15 of Fig. 1. The cap 14 of Fig. 3 has shallow rim portions 16, 16, and deeper rim portions 17, 17, that are formed respectively from the parts 18 and 19 of Fig. 1. The dotted lines 20 in Fig. 1 indicate where the rim of the cap is turned down when drawn in the die to form the rim of the cap.

The cap rim 22 is made slightly larger 105 than the upper part 23 of the container, so as to allow the edges of the rim to be turned in as at 25 in Fig. 2. This turning in of the rim edge assists in centralizing the cap on the jar. The edges 17 of the rim are also turned in as at 25 and 26 in Fig. 4. The 110 hands will not be cut by the curving in of these edges when handling the package.

The cap 14 is also provided with a pair of oppositely disposed short spring catches 28, 28, and with two pairs of oppositely disposed long spring catches 29, 29 and 30, 30. These 5 spring catches are punched in the deep portions 17 of the rim, and they are bent inwardly as at 31, 31 in Fig. 4.

The gasket 32 is placed in the inner corner of the cap 14; it may be of rubber or composition, and it may be cemented in place.

When a cap 14 is placed on the tumbler 10, the gasket 32 will rest on the rim 11 of the tumbler. In pressing the cap down, the spring catches 28, 29 and 30 will be sprung outwardly. But when the shorter catches 28, 28 pass the shoulder 12 of the tumbler, they will spring inwardly and engage the under part of the enlarged top 23 of the jar at the time that the gasket 32 rests on the rim 11 15 of the tumbler, thus preventing the contents from being pumped out of the container. This position is shown in Fig. 5, where the package is placed below the presser 35, ready to have the air exhausted from the container.

In Fig. 6 the air is assumed to have been exhausted from the container, and the plunger 35 has descended on the cap 14, compressing the gasket 32, and bringing the catches 30 a little below the shoulder 12 and permitting them to spring inwardly and under the shoulder 12 of the tumbler. As the plunger 35 rises, after the sealing operation, the gasket 32 expands a little, thus allowing the catches 30 to engage the shoulder 12, and 35 add its holding power to the atmospheric pressure exerted on the cap 14.

The number of short or long catches may be modified but not less than two oppositely disposed catches are required.

The shoulder 12 is made annular, so that the catches will engage at any part of the shoulder 12. This annular shoulder is preferably made quite shallow, and square cornered, in order to allow the thin spring catches to engage it.

To readily open this closure, a knife or other pointed tool is injected under the spring catches at 36, so as to spring the catches outwardly to disengage them from the shoulder 12; and when thus disengaged, the further insertion of the tool will spring the cap rim away from the gasket, and admit air to the interior of the container.

To replace the cap and make it hold on the jar, the catches are sprung inwardly as in Fig. 4, and when the cap is pushed down on the tumbler, the catches will engage the shoulder, and thus hold the cap securely on the jar.

This closure which is adapted to seal articles by the well known vacuum method, is also adapted to seal cold articles such as pickles, fish and other articles. This is accomplished by packing the container, placing the cap and gasket on rim of the con-

tainer, then forcing the cap downwardly by any pressing means, so as to cause the catches to engage the shoulder on the container.

In processing hot goods it is preferable to heat the container; then the hot food is poured into the container, and the cap is placed on the container and pressure is applied on the cap while the package cools; when cooled the cap will be held on by atmospheric pressure. This pressure must be sufficient to bring the catches below the shoulder of the container.

Various modifications may be made in this closure without departing from the spirit of the invention.

I hereby claim as my invention:

1. The method of hermetically sealing a package comprising a sharp shouldered jar, a cap having inwardly bent spring catches of different lengths and a resilient gasket in the cap, which consists in pressing the cap and the gasket upon the jar, until the shorter spring catches engage the jar shoulder; then exhausting the air from the jar, then compressing the cap and gasket still more, until the longer catches engage the jar shoulder; then releasing the pressure on the cap, allowing the gasket to expand, and thereby causing the catches to engage with the shoulder of the jar.

2. A closure for containers, comprising a cap having shallow and deep rim portions, the deep portions being provided with oppositely disposed inwardly bent spring catches of different lengths, and having a resilient gasket in the cap.

3. A closure for a container, having a plurality of resilient inwardly bent catches, formed in the rim thereof, the catches being oppositely disposed in pairs, the pairs of catches being of different lengths.

4. The combination of a container with a cap provided with resilient inwardly bent catches of different lengths, the operative edges of the catches being in different planes to engage a shoulder on the container at different times during the sealing operation.

5. In combination a container having an external shoulder adjacent its mouth, a cap having a rim and a compressible gasket between the top of the cap and the upper edge of the container, and adapted to be compressed during the sealing operation, said cap having a plurality of sets of angularly bent fingers, or catches, the catches of each set being angularly spaced at substantially equal distances, the operative edges of the several sets of catches being in different planes, to successively engage said shoulder.

Signed at Hartford, Connecticut, this 10th day of March, 1923.

WILLIAM A. LORENZ.
